PORATION OF DELAWARE

PROCESS AND APPARATUS FOR MANUFACTURING FINELY DIVIDED CARBON

Application filed July 7, 1928. Serial No. 291,096.

This invention relates to a method of manufacturing finely divided carbon, such as is commonly called lamp black or carbon black, in a simple and efficient manner and to an apparatus by means of which the process may be readily controlled and regulated. The method and apparatus are particularly designed and adapted for the manufacture of finely divided carbon from hydrocarbon oil such as petroleum.

An object of this invention is to provide a method of manufacturing a finely divided carbon of uniform grade in a continuous manner.

Another object is to provide a method of increasing the capacity of any process of manufacturing lamp black.

Another object is to provide a method of controlling the combustion temperatures during the manufacture of finely divided carbon from petroleum or other hydrocarbon oil.

Another object is to provide a method of accurately controlling the quality of finely divided carbon made from petroleum or other hydrocarbon in oil.

Another object is to provide a method for manufacturing finely divided carbon from petroleum or other hydrocarbon oils, wherein air supplied for combustion of petroleum oils is controlled by the quantity of air introduced for cooling purposes.

Another object is to provide means for regulating the combustion of a hydrocarbon oil during the manufacturing of finely divided carbon.

A still further object is to provide means for controlling the combustion temperatures of petroleum or other hydrocarbon oils during the manufacture of finely divided carbon therefrom.

Another object is to provide means whereby air supplied for combustion of petroleum or other hydrocarbon oils is controlled by the quantity of air introduced for cooling purposes.

Although it has been well known that incomplete combustion of oil will result in the formation of finely divided carbon, lamp black, or what is commonly termed as "smoke", there has been a great deal of dif-

ficulty encountered in producing lamp black in this manner, and it has been particularly difficult to produce a product of uniform and specified quality. The temperatures at which oil is burned under reducing conditions, or under such conditions as produce incomplete combustion and large quantities of finely divided carbon, exert a material effect upon the fineness, tar content, color and tinting strength of the final product. A fairly large burner having an area of oil burning under conditions of incomplete combustion will present difficulties, in that the outer edges of the area of burning oil are more completely oxidized and, therefore, the temperature of combustion at these points is considerably higher than the temperature of combustion in the central portion of the burning oil area. Operation under these conditions results in the formation of various forms of lamp black or carbon, and in an inferior product.

We have ascertained that a lamp black or carbon with a blue undertone has a very low tinting strength, while a lamp black or carbon having a red undertone, has a very high tinting strength. Both of these two grades of carbon can be made simultaneously in an apparatus such as is commonly used and the final product is of poor quality. We have found that those grades of lamp black having a high tinting strength, may be made by maintaining the combustion temperatures at relatively low ranges. Although it is relatively easy to maintain a low combustion temperature over a small total area of burning oil surface, such regulation applied to a large total surface has been extremely difficult, if not impossible. Our invention provides a means for maintaining the temperature of combustion over a large total area within close limits and provides a method of regulating the temperature of combustion in a novel and most effective manner.

In describing our invention, reference shall be had to the appended drawing which illustrates one form of apparatus which may be used in carrying out the method herein described and one modification of an apparatus which we have invented for the purposes hereinafter more clearly described.

It will be understood, however, that we are not limited to the exact construction, arrangement and combination of elements shown in the drawing, as the apparatus shown therein is purely for illustrative purposes, and numerous modifications and changes may be made without departing from the scope of our invention.

Referring to the drawing, which, as has been stated before, shows an apparatus partly in section adapted to carry out our invention, a suitable retort furnace or combustion zone 10 is provided having the burner pan 11 mounted therein. A plurality of pipes, ducts or other air supply means are sealed through the bottom of the burner pan 11, the upper edges of the air supply means 12 terminating in a plane slightly below the outer edges of the burner pan 11.

20 The burner pan 11 may be continuously supplied with a suitable oil from any suitable source, such as, for example, a tank 13 connected by means of pipe line 14 with the burner pan 11. A control valve 15 may be placed in the line 14 so as to regulate the quantity of oil supplied to the burner pan. 25 The oil undergoes incomplete combustion in the burner pan 11 and a temporary excess of oil supplied to the burner pan 11 through pipe line 14, will be discharged therefrom through the air ducts 12 to the pit 16, beneath the combustion chamber, by reason of the fact that the upper ends of the air ducts 12 are below the plane of the 30 outer edges of the burner pan 11. This particular construction prevents the burning oil from overflowing into the space surrounding the burner pan 11, and thereby interfering with a uniform regulated combustion of the oil. 35 Excess oil discharged from the combustion chamber through air ducts 12 may be caught in the pit 16 in a suitable tank or other container. An auxiliary damper 17 may be provided beneath the lower end of the air ducts 12, suitable means being provided for regulating the damper 17, such means not being shown in the drawing. The space between the damper 17 and pit 16 may be open 40 to the air to permit air to be admitted to the air ducts 12. 45 50

The combustion gases from the combustion chamber 10 are discharged by pipe means 18 into a separating apparatus adapted to remove coarse particles of carbon, tarry matters and the like, from the combustion gases. Such separating apparatus may consist of a substantially air-tight drop-out drum 19 provided with a conical bottom 20 and a valved outlet 21 in the lower portion of said conical bottom. The pipe line 18 connecting the combustion or reduction chamber 10 with the drop-out drum 19 may terminate within the drum 19 in a lower horizontal plane than that of an outlet 22, leading away from the drop-

out drum 19 from a point near the upper portion thereof.

Pipe line 22 may communicate with a suitable means for cooling the purified combustion gases discharged from the primary separating apparatus or drop-out drum 19. As shown in the drawing, the pipe line 22 communicates with another pipe line 23, which leads to an exhauster or other fan 24, said exhauster 24 being preferably operated at a constant speed, so that a constant volume of combustion gases are being continuously withdrawn from the drop-out drum 19 and from the combustion or reduction chamber 10. In other words, the entire system from the combustion zone to the exhauster 24 is maintained under a partial pressure or vacuum. An air valve 25 in communication with the atmosphere or other source of cool air at a greater pressure than that existing in line 23, may be provided in the pipe line 23 so as to admit air for cooling purposes into the system. It will be understood that if more air is admitted or sucked in through the valve 25, then a smaller proportion of air will be admitted to the system through the air ducts 12. In this manner, the supply of air for the purposes of regulating the temperature of combustion in the burner pan 11 and combustion zone 10 is regulated by the admission of cooling air through the valve 25.

The cooled products of combustion are then discharged by means of the exhauster and constant speed fan 24, through suitable means such as the pipe line 26, into a final separating apparatus adapted to remove and separate finely divided carbon particles from the combustion gases. 100

The apparatus shown in the drawing for illustrative purposes, consists of a manifold 27 into which the pipe line 26 discharges the combustion gases. Collecting bags 28 may be suspended from the manifold 27, the collecting bags 28 being of sufficiently fine texture to retain the finely divided carbon present in the combustion gases, but sufficiently permeable or pervious so as to allow the dust-free gases to be discharged therethrough. The collecting bags 28 may be provided with outlets 29 through which finely divided carbon collected in the bags may be removed for packing, storing, shipping and other purposes.

A release valve 30 may be provided in the manifold 27, said release valve being capable of discharging the products of combustion from the manifold, whenever the pressure within the manifold 27 and collecting bags 28 exceeds a predetermined pressure. Pressure may be built up within the manifold 27 and collecting bags 28 by the accumulation of a layer of finely divided carbon upon the inner surface of the collecting bags, thereby increasing the impermeability or resistance to the

passage of gas through the walls of the collecting bags.

It will be understood that the collecting means herein described are merely for purposes of illustration and although such means are extremely effective and have the further advantage of being very simple, other means may be substituted therefore without departing from the spirit of this invention.

10 Another modification may consist in admitting air for cooling purposes into the system at the pipe line 18 instead of admitting such air into the pipe line 23. The admission of cooling air into the system at pipe line 18 may have certain advantages over the arrangement shown in the drawing, in that tarry materials present in the gases of combustion may be somewhat cooled and condensed before reaching the primary separating apparatus or 15 drop-out drum 19, thereby more thoroughly cleansing the combustion gases of undesirable constituents.

20 The burner pan 11 may be made of any suitable material such as metal, refractory-ware and the like. Air may also be admitted to the reduction or combustion chamber 10 by means of openings formed between the outer edges of the burner pan 11 and the supports upon which it rests in the bottom of the combustion zone.

25 The admission of air uniformly over the entire area of the surface of the burning oil in the burner pan 11, prevents localized increase in combustion temperatures, permits a more careful and accurate control of the combustion temperatures, and thereby insures a more uniform quality of product, a larger capacity for the same area of burning oil surface and permits the production of those 30 grades of finely divided carbon, lamp black, carbon black and the like, which are only obtained by the use of controlled temperatures of incomplete combustion.

35 The operation of the system and apparatus hereinabove described will be evident to those skilled in the art, and it is not deemed necessary to go into further details. It may be stated, however, that temperature control instruments such as pyrometers may be placed 40 in the upper portion of the combustion chamber, in the primary separating apparatus or drop-out drum and in the pipe line 26, so that an accurate control may be maintained of the entire operation. Furthermore, a 45 pressure gage or manometer may be connected to the system near the junction of pipe line 26 with manifold 27, so as to prevent over-loading the collection bags 28. These and other operating details come within the scope 50 of changes and modifications which anyone skilled in the art may make.

We claim:

1. A method of manufacturing finely divided carbon from petroleum oil comprising, 55 maintaining an area of petroleum oil under-

going independent incomplete combustion in a combustion zone, continually admitting air at a plurality of points within and on said area of petroleum oil, regulating the quantity of air being admitted to maintain an incomplete combustion over the entire area of oil within required temperature limits without the supply of extraneous and separate heat to the oil, cooling the products of combustion and then separating solid carbon particles from such cooled products of combustion. 70 75

2. A method of manufacturing finely divided carbon from petroleum oil comprising, maintaining an area of petroleum oil undergoing incomplete combustion in a combustion zone, continuously admitting air in a plurality of points within and on said area of petroleum oil, regulating the quantity of air being admitted to maintain uniform incomplete combustion over the entire area of oil, separating tarry and coarse, solid particles from the products of combustion, cooling the purified products of combustion and then separating solid carbon particles from such cooled products of combustion. 80 85

3. A method of manufacturing finely divided carbon from petroleum oil comprising, maintaining an area of petroleum oil in a combustion zone, continually admitting air at a plurality of points on said area of petroleum oil, exhausting products of combustion from said combustion zone by the application of a constant volume suction to the system, introducing cooling air into the system between the combustion zone and source of suction, and regulating the quantity of air admitted to the combustion zone by varying the quantity of cooling air admitted into the system between the combustion zone and 100 source of suction. 105

4. A method of manufacturing finely divided carbon comprising, maintaining an area of oil capable of combustion in a combustion zone, continually admitting air at a plurality of points on said area of oil in quantities insufficient to cause complete combustion, exhausting products of combustion from said combustion zone by applying a constant volume suction to the system, introducing cooling air into the system between the combustion zone and source of suction and regulating the temperature of combustion within said combustion zone by varying the quantity of cooling air admitted into the system. 110 115 120

5. A method of manufacturing finely divided carbon comprising, maintaining an area of oil capable of combustion in a combustion zone, continually admitting air at a plurality of points on said area of oil in quantities insufficient to cause complete combustion, exhausting products of combustion from said combustion zone by applying a constant volume of suction to the system, introducing cooling air into the system between the com- 125 130

bustion zone and source of suction, regulating the temperature of combustion within said combustion zone by varying the quantity of cooling air admitted into the system and then separating finely divided carbon from the cooled combustion gases.

6. An apparatus for manufacturing lamp black from a combustible oil comprising, a combustion chamber, a burner pan within said combustion chamber, means for supplying a combustible oil to said burner pan, a plurality of means for introducing air to the surface of the burner pan at a plurality of points, means for separating solid particles

15 from the combustion gases, means for conducting combustion gases from said combustion chamber to said separating means, said conducting means including a suction means for withdrawing combustion gases from said combustion chamber, and means for introducing cooling air into said conducting means at a point between said suction means and combustion chamber.

7. An apparatus for the manufacture of lamp black from petroleum oil comprising, a combustion chamber, a burner pan within said chamber, means for supplying petroleum oil to said burner pan, a plurality of means for introducing air to the surface of the burner pan at a plurality of points, means for separating coarse material from combustion gases, pipe means connecting said combustion chamber and coarse material separating means, means for separating finely divided carbon from combustion gases, pipe

30 means connecting the coarse material separating means and fine carbon separating means, suction means in said last named pipe means, said suction means being adapted to discharge gases into said fine carbon separating means, and means for introducing cooling air into said last named pipe means at a point between said coarse material separating means and suction means.

40 8. An apparatus for the manufacture of finely divided carbon from petroleum oils comprising, a combustion chamber, a burner pan within said chamber, means for supplying petroleum oil to said burner pan, means for introducing air to the surface of the burner pan at a plurality of points comprising a plurality of spaced air ducts passing through the bottom of said burner pan, the upper ends of said air ducts terminating below the level of the top edges of said burner

45 pan, means for cooling combustion gases, means for separating finely divided carbon from said combustion gases, and pipe means connecting said combustion chamber, cooling means and separating means.

9. A method of manufacturing finely divided carbon comprising maintaining an area of oil capable of combustion in a combustion zone, continually admitting air at a plurality

50 60 65 70 75 80 85 90 95 100 105 110 115 120 125 130

tities insufficient to cause complete combustion, exhausting products of combustion from said combustion zone by applying a constant volume of suction to the system, introducing cooling air into the system between the combustion zone and source of suction, regulating the temperature of combustion within said combustion zone by varying the quantity of cooling air admitted into the system, separating tarry and coarse solid particles from the products of combustion before introducing cooling air thereinto, and separating finely divided carbon from the cooled combustion gases.

10. An apparatus for manufacturing lamp black from a combustible oil comprising, a combustion chamber, a burner pan within said chamber, means for supplying combustible oil to said burner pan, means for introducing air to the surface of oil in said burner pan at a plurality of points, said means comprising a plurality of spaced air ducts passing through the bottom of said burner pan, the upper ends of said air ducts terminating below the level of the top edges of said burner pan, means for separating solid particles from the combustion gases, means for conducting combustion gases from said combustion chamber to said separating means, said conducting means including a suction means for withdrawing combustion gases from said combustion chamber, and means for introducing cooling air into said conducting means at a point between said suction means and combustion chamber.

Signed at Richmond, Cal., this 27th day of June 1928.
